UNITED STATES PATENT OFFICE.

BENJAMIN S. SEAMAN, OF CANTON, OHIO.

DESIGN FOR A SPRING.

SPECIFICATION forming part of Design No. 29,022, dated July 12, 1898.

Application filed May 20, 1898. Serial No. 681,261. Term of patent 7 years.

To all whom it may concern:

Be it known that I, BENJAMIN S. SEAMAN, a citizen of the United States, residing at Canton, in the county of Stark and State of Ohio, 5 have invented a new and original Design for Springs, of which the following is a specification.

My invention relates to a new and original design for springs; and it consists of a spring 10 of the configuration shown in the accompanying drawings, in which—

Figure 1 is a top perspective view, and Fig. 2 is a side elevation.

The leading feature of the design comprises 15 the parallel downwardly-curved arms 1, which converge at the points *a* to the points *b* and

then extend parallel and horizontal, as shown at 2, while the rear ends of the arms curve laterally in opposite directions and thence inwardly to form the curve *c* and lie in substantially the same horizontal plane as the ends 2.

What I claim is—

The design for a spring as herein shown and described.

In testimony whereof I have hereunto set my hand in the presence of two subscribing witnesses.

BENJAMIN S. SEAMAN.

Witnesses:

CHAS. R. MILLER,
CHAS. M. BALL.
